US0D1103294S

(12) **United States Design Patent** (10) **Patent No.:** **US D1,103,294 S**
(45) **Date of Patent:** **** Nov. 25, 2025**

(54) **TOY PIECE**

(71) Applicant: **Idea Vault Holdings, Inc.**, Ashland, OR (US)

(72) Inventors: **Joshua J Gedlick**, Ashland, OR (US); **Howard Allen Wilson, IV**, Medford, OR (US); **Jordan Michael Willing**, Ashland, OR (US)

(73) Assignee: **Idea Vault Holdings, Inc.**, Ashland, OR (US)

(**) Term: **15 Years**

(21) Appl. No.: **29/949,678**

(22) Filed: **Jun. 27, 2024**

Related U.S. Application Data

(62) Division of application No. 29/720,593, filed on Jan. 14, 2020, now Pat. No. Des. 1,048,229.

(51) **LOC (15) Cl.** **21-01**

(52) **U.S. Cl.**

USPC **D21/484**; D21/561

(58) **Field of Classification Search**

USPC D21/483-484, 487-488, 495, 505, 561; D23/250, 252, 253

CPC A63H 33/08; A63H 33/06

(57) **CLAIM**

The ornamental design for toy piece, as shown and described.

DESCRIPTION

FIG. 1 is a right plan view of a toy piece, showing our new design.

FIG. 2 is a front plan view of FIG. 1;

FIG. 3 is a left plan view of FIG. 1;

FIG. 4 is a rear plan view of FIG. 1;

FIG. 5 is a top plan view of FIG. 1;

FIG. 6 is a bottom plan view of FIG. 1;

FIG. 7 is a top perspective view of FIG. 1; and,

FIG. 8 is a bottom perspective view of FIG. 1.

1 Claim, 8 Drawing Sheets
